UNITED STATES PATENT OFFICE.

CHARLES PFAU, OF CINCINNATI, OHIO, ASSIGNEE TO THE PFAU MANUFACTURING COMPANY, OF NORWOOD, OHIO, A CORPORATION OF OHIO.

HINGE FOR WATER-CLOSET SEATS.

1,127,919.

Specification of Letters Patent.

Patented Feb. 9, 1915.

Application filed April 29, 1910. Serial No. 558,480.

To whom it may concern:

Be it known that I, CHARLES PFAU, a citizen of the United States, residing at Cincinnati, in the county of Hamilton and State 5 of Ohio, have invented certain new and useful Improvements in Hinges for Water-Closet Seats, of which the following is a specification.

My invention relates to improvements in 10 water-closet seat construction; and the object is to provide a simple self-contained hinge which will stand far back from the rear end of the seat, whereby its metal parts are not exposed to contamination, thus 15 guarding against corrosion and deterioration of the metal parts as well as eliminating danger to the occupant of the seat from contact with the contaminated metal parts.

The especial object is to provide a hinge 20 having the above characteristics well suited for a seat which comprises two separate and distinct parts, which must be held in their proper spaced relation at the rear by the hinge structure, and which are usually held 25 in proper relation to each other at the front by a suitable handle means.

My invention consists in the parts and 30 in the details of construction and arrangement of parts as will hereinafter be more fully described and claimed.

In the drawing: Figure 1 is a bottom plan view of a seat and its cover provided with my improved hinge; and Fig. 2 is a vertical cross section on the line 2-2 of 35 Fig. 1.

In the construction illustrated to exemplify the use of my invention, the bowl 1, of ordinary construction, has a seat which comprises the two side sections 2 and 3 40 spaced apart and connected together at the front by means of a handle 4.

My improved hinge comprises the bifurcated members 5 which are secured to the seat sections 2 and 3, respectively, near their 45 rear ends. These members 5 are pivotally connected to a pintle 6, as will be more fully described. The seat is preferably provided with a lid or cover 7, which is also pivotally connected to the pintle 6 by means of a 50 hinge plate 8 having arms 9 and 10 with ears embracing the pintle between the bifurcated members 5; but this lid or cover may be omitted if desired, as it forms no 55 part of my invention, and the omission thereof will have no effect upon the con-

struction or operation of the parts forming my invention. The bifurcations of the members 5 embrace the pintle 6 and flank the ears or projections 12 upon the upper ends of the posts 11, said posts being mounted 60 on the bowl 1 and thereby holding the seat sections in proper spaced relation to each other at the rear. Each outer bifurcation of a member 5 has its ear provided with a closed end 13 which limits end play of the 65 pintle 6. The handle at the front may be provided with buffers 14, and the parts of the bifurcated hinge members that are secured to the seat sections may also be provided with buffers 15.

When the entire hinge is assembled in connection with the separate seat sections, the bifurcations of its members 5, flanking the posts 12 closely, serve to maintain the spacing of the seat sections independently 75 of any other element, such as the cover hinge plate 8, which, as before stated, may be provided or omitted as desired. At the same time, by providing the single pintle 6 extending from one post to the other, and with 80 its ends inclosed by the closed ends 13 of the outer bifurcations of the members 5, the pintle 6 effectively maintains proper alignment of the rear parts of the seat sections in a single plane, and distributes the strain 85 to both posts, while being effectively held in position without the use of any additional elements, such as nuts or pins. By such arrangement the number of spaces for the collection of obnoxious substances is minimized 90 and the structure thereby rendered more sanitary, aside from the remoteness of its location from the region of the seat where it would be likely to be contaminated. The simple construction of my improved hinge 95 also makes it more economical to produce and more readily assembled.

Having fully described my invention, what I claim as new and desire to secure by Letters Patent is:

A hinge for a water-closet seat, comprising separate hinge members, each composed of a forward plate for attaching it to the seat, and a part with bifurcations, extended back a material distance from the plate, 105 with transversely aligned bearings in said bifurcations, posts, a respective one of which is received between the bifurcations of each hinge member, with a bearing aligned with the bearings of the hinge member, a pintle 110

extending through all of the bearings of the bifurcations and of the posts and forming the pivot between the posts and the hinge members, said posts being adapted to be rigidly attached to a lower fixed part of the water-closet structure, and the laterally outward bifurcations on each of said hinge

members having its bearing outwardly closed against the adjacent end of the pintle and thereby retaining the pintle in position.

CHARLES PFAU.
